UNITED STATES PATENT OFFICE

2,151,471

MINER'S LAMP BRACE

James H. Horsley, Chicago, Ill., assignor to Universal Lamp Company, Chicago, Ill., a corporation of Illinois

Application February 3, 1937, Serial No. 123,827

4 Claims. (Cl. 240—60)

This invention relates to improvements in acetylene lamps, particularly the type designed for miners' use.

- Lamps of this character are usually provided with means for supporting and sustaining the same on a miner's cap. The means for this purpose includes a hook disposed at the rear of the lamp body, and a brace also extending from the rear of the lamp.
- 10 It is the main object of this invention to provide in a miner's lamp of the character described, an improved brace which may be readily and detachably secured in operative position to the lamp, thereby facilitating its removal from or 15 attachment to the lamp whenever that becomes necessary or desirable.
- Another object of the invention is to provide in a miner's lamp of the character described, a brace having novel and improved means for detachably 20 securing the same to the lamp body.

A further object of the invention is to provide in a miner's lamp of the character described, a brace having novel and improved means for detachably securing the same to the lamp body, 25 which means will be simple in construction and assembly, durable in use, and at the same time highly efficient for carrying out the purposes for which it is designed.

With the foregoing and other objects in view, 30 which will appear as the description proceeds, the invention consists in certain novel features of construction, arrangement and combination of parts hereinafter fully described, illustrated in the accompanying drawings, and particularly 35 pointed out in the appended claims, it being understood that various changes in the form, proportion, size and minor details of the structure may be made without departing from the spirit or sacrificing any of the advantages of the in- 40 vention.

For the purpose of facilitating an understanding of my invention, I have illustrated in the accompanying drawing, a preferred embodiment thereof, from an inspection of which, when con- 45 sidered in connection with the following description, my invention, its mode of construction, assembly and operation, and many of its advantages should be readily understood and appreciated.

Referring to the drawing in which the same 50 characters of reference are employed to indicate corresponding or similar parts throughout the several figures of the drawing:

Fig. 1 is a side elevational view of a miner's lamp attached to a cap, said lamp embodying the 55 present invention;

Fig. 2 is a view in perspective of the cap support and miner's lamp in disassembled position, the lamp, with the exception of the hook and brace, being shown in dot and dash lines;

Fig. 3 is a sectional view taken substantially 5 on line 3—3 of Fig. 4;

Fig. 4 is a sectional view taken substantially on line 4—4 of Fig. 3.

The present invention provides a simple and convenient improvement in the construction and 10 equipment of miners' lamps, whereby any injury to the brace by means of which the lamp is attached to the miner's cap, may be readily replaced with a new brace by simply removing the injured brace and substituting a new brace in its stead, 15 the entire operation being accomplished by merely removing a single screw, by means of which the brace is rigidly held in operative position on the lamp.

The nature of the improvement will be clearly 20 understood from the illustrations in the drawing, in which the reference numeral 10 designates the body portion of a miner's lamp of well-known design and construction, which body portion carries the water reservoir, water feed control, burner and reflector, as well as the carbide container 11, which is secured to the lower portion of the body portion 10 of the lamp.

The lamp is adapted to be suspended and positioned on the miner's cap 12, to the front portion 30 of which is secured in any suitable and well-known manner, the supporting plate 13. This plate is generally formed of sheet metal and is provided at its upper end with an opening 14, through which the stem 15 of the hook 16 is 35 adapted to pass. The shank 17 of the hook 16 is adapted to be received in the guide slot 18 provided in the plate 13 when the lamp is in operative position on the cap, to hold the lamp against lateral movement when in such position. 40 To further insure a substantially rigid connection between the lamp and cap, there is provided a brace generally designated by the reference character 19, and provided with a pair of resilient or spring wire arms arranged for resiliently 45 gripping the side edges of the plate 13 to securely hold the lamp on the plate. In the embodiment illustrated, the brace 19 is constructed from spring wire which is bent to form the arcuate arms 20 and 21, which arms extend rearwardly from the 50 body of the lamp as shown in Fig. 4 of the drawing. Said arms 20 and 21 are provided adjacent their free ends with inwardly extending substantially V-shaped portions 22 and 23, which portions are adapted to snap past the side edges 55

of the plate 13 to thereby rigidly grip the said plate when the lamp is arranged in operative position on the plate. Intermediate the arms 20 and 21, the wire is bent to provide an upstanding portion 24 of substantially inverted U-shaped formation, with the leg portions of said portion 24 lying in a plane substantially perpendicular to the plane of the arms 20 and 21 and being substantially parallel to each other. A strip of resilient material 25 such as, for example, sheet metal or the like is mounted on said portion 24, said strip spanning the distance between the legs of the portion 24 and being secured to said portion 24 by curling the side edges of said strip around said leg portions as shown more clearly in Fig. 4 of the drawing.

The brace 19 is detachably secured to the lamp body by providing on the hook 16 a depending offset portion 26, which is of such a size as to snugly fit between the curled-in edges of the metal strip 25, and to thereby prevent any swaying movement of the lamp at this point. The depending offset portion 26 is provided with a central screw-threaded opening 27 which is in alignment with a central opening 28 provided in the metal strip 25. A screw 29 having a head 30 is adapted to pass through the opening 28, and to be threaded into the threaded opening 27 and to thereby detachably secure the brace to the lamp body. The resiliency of the metal strip 25 and its arrangement on the portion 24 is of such a character as to cause said strip 25 to act as a lock washer when the brace is in fully assembled position on the lamp body, thereby avoiding the danger of the screw 29 becoming loose or disengaged from its screw-threaded opening 27.

From the foregoing, it will be noted that I have provided a simple and inexpensive mechanism for detachably securing a brace to the lamp whereby any injury to the brace will not render the lamp useless, as a new brace may be readily secured in place by the simple operation of removing and replacing a single screw.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. The combination with a miner's lamp having a hook, one arm of which is rigidly secured to the lamp body, said last-mentioned arm having a depending offset portion, of a detachable brace, formed of resilient material, comprising a pair of outwardly extending arms, an upstand-

ing substantially inverted U-shaped portion formed intermediate said arms and integral therewith, a strip of resilient material spanning said inverted U-shaped portion, and means including a single screw for detachably securing said strip to said depending offset portion of said hook, said strip acting as a lock washer to prevent loosening of said screw.

2. The combination with a miner's lamp having a hook, one arm of which is rigidly secured to the lamp body, said last-mentioned arm having a depending offset portion, of a detachable brace, formed of resilient material, comprising a pair of outwardly extending arms, an upstanding substantially inverted U-shaped portion formed intermediate said arms and integral therewith, a strip of resilient material spanning said inverted U-shaped portion, with the side edges of said strip secured to the leg portions of said inverted U-shaped portion, and means including a single screw for detachably securing said strip to said depending offset portion of said hook, said strip acting as a lock washer to prevent loosening of said screw.

3. The combination with a miner's lamp having a hook, one arm of which is rigidly secured to the lamp body, said last-mentioned arm having a depending offset portion, of a detachable brace, formed of resilient material, comprising a pair of outwardly extending arms, an upstanding substantially inverted U-shaped portion formed intermediate said arms and integral therewith, a strip of resilient material spanning said inverted U-shaped portion, and being secured thereto by curling the side edges thereof around the leg portions of said inverted U-shaped portion, and means including a single screw for detachably securing said strip to said depending offset portion of said hook, said strip acting as a lock washer to prevent loosening of said screw.

4. The combination with an acetylene lamp having a hook, one arm of which is rigidly secured to the lamp body, said last-mentioned arm having a depending offset portion, of a brace formed of resilient material, comprising a pair of outwardly extending arms, an upstanding substantially inverted U-shaped portion formed intermediate said arms and integral therewith, a strip of resilient material spanning said inverted U-shaped portion with the side edges thereof secured to the leg portions of said inverted U-shaped portion, the distance between said leg portions of said inverted U-shaped portion being such as to receive there-between the said depending offset hook portion, said offset hook portion being provided with a screw-threaded opening and a screw passing through said strip and threaded into said screw-threaded opening of said offset hook portion for securely fastening the brace to the lamp body.

JAMES H. HORSLEY.
